UNITED STATES PATENT OFFICE.

THOMAS H. LAVIER, OF DALLAS, TEXAS.

WRENCH.

No. 849,248.

Specification of Letters Patent.

Patented April 2, 1907.

Application filed April 30, 1906. Serial No. 314,533.

To all whom it may concern:

Be it known that I, THOMAS H. LAVIER, a citizen of the United States, residing at Dallas, in the county of Dallas, State of Texas, have 5 invented certain new and useful Improvements in Wrenches; and I do hereby declare the following to be a full, clear, and exact description of the invention, such as will enable others skilled in the art to which it appertains to make and use the same.

This invention has relation to wrenches generally, but is particularly designed for employment on pipes, and hence falls in the class commonly called "pipe-wrenches."

15 It is the object of the invention to provide improvements that will enhance the efficiency of pipe-wrenches in points of strength, quickness of action, durability, and certainty of operation, as well as improvements that will 20 make them capable of doing the work of ordinary pipe-wrenches, and, beside, of supplanting the functions of specially-designed tools— as, for mere example, that of chain tongs or wrenches.

25 Of the drawings, Figure 1 is a side elevation of my improved pipe-wrench, partly broken away. Fig. 2 is a transverse section through the front saddle of the wrench. Fig. 3 is a transverse section through the rear 30 saddle of the wrench.

In the drawings, 5 designates the handle and stationary bar provided on its forward end with a removable jaw 6.

7 designates the sliding or adjustable bar 35 provided on its forward end with a fixed jaw 8, as is usual in wrenches of this class.

Immediately to the rear of the jaws is the front saddle or strap 9, that passes over the sliding bar and downward, engaging the sides 40 of the said bar and the sides of the fixed bar between two parallel ribs 10 and 11 formed on the latter part.

12 is a helical spring resting on the strap 13, connecting the lower ends of the saddle 9 below the bar 5 and at its upper end extending up into a recess 14 in the bar 5. The said spring operates to yieldably hold the saddle 9 down on the bar 7.

50 The bottom surface of the bar 5, rearwardly of its jaw for a necessary distance, is provided with what may be called "rearwardly-inclined teeth" 15, that are adapted to fit and engage the forwardly-inclined teeth 16, formed on the upper side of the strap 17, extending longitudinally between the legs 18

of the main or rear saddle 19. The latter is made substantially hollow in its upper part, through which the upper or sliding bar 7 passes and has the aforesaid depending legs extending down and engaging the sides of the 60 bar 5.

The main saddle 19 is formed with a partition 20, which is engaged by the pending projection 21 on the rear end of the sliding bar 7 when the wrench is in use. 65

A bowed spring 22 is secured at its middle to the under side of the bar 7 and has its ends resting upon the upper surface of the bar 5. Its tendency is to yieldably hold the teeth 15 and 16 in engagement one with the other, 70 but at the same time to allow the main saddle to be depressed and said teeth to be disengaged, so that the bar 7, with the saddles, may be adjusted back and forth on the bar 5 to bring the jaws into contact with the 75 pipe.

A screw-threaded bolt 23 is tapped through the main saddle and passes through the bar 7, holding the latter in place and allowing of a slight rocking of the bar 7 thereon 80 on operating the handle to release the pipe gripped between the jaws.

It will be understood by those skilled in the art that in the operation of the wrench it will act with great force in tending to turn 85 the pipe gripped by the jaws and that there will be relatively little or no tendency to crush the pipe between the jaws.

What is claimed as the invention is—

1. In a pipe-wrench, the combination 90 with the handle-bar and its jaw, the movable bar and its jaw, the front saddle engaging both bars, teeth on the handle-bar, the main saddle on the movable bar provided with a partition extending from side to side 95 below the latter bar and having teeth engaging the teeth on the handle-bar, the movable bar being further provided with a projection to engage said partition.

2. In a pipe-wrench, the combination 100 with the handle-bar and its jaw, vertical parallel ribs on the sides of the handle-bar in rear of its jaw, teeth on the under side of said bar, of the front saddle extending over the movable bar and downward along the 105 sides of the handle-bar between said vertical ribs, a spring interposed between the lower part of the forward saddle and the handle-bar for drawing the said saddle down on the movable bar, the main saddle on the mov- 110

- able bar provided with teeth engaging the teeth on the handle-bar, means for maintaining the main saddle in position on the movable bar, and a spring disposed between the two bars and operating with a tendency to separate them and to keep the said teeth in engagement with each other, and adapted to be compressed to disengage the said teeth.
- 10 3. In a pipe-wrench, the combination of the handle and its jaw, the said bar having teeth on its under side and provided on its sides with vertical guides, of the movable bar and its jaw, the front saddle engaging both bars and arranged between the said vertical guides on the fixed jaw, a spring interposed between the front saddle and the movable jaw and operating with a tendency to separate the same, the main saddle on the
- 15 movable bar provided with a partition extending from side to side below the latter bar and having teeth engaging the teeth on the handle-bar, the movable bar being fur-

ther provided with a projection to engage the said partition.

4. In a pipe-wrench, the combination with the handle-bar and its jaw, the movable bar and its jaw, the front saddle engaging both bars, teeth on the handle-bar, the main saddle on the movable bar provided with a partition extending from side to side below the latter bar and having teeth engaging the teeth on the handle-bar, the movable bar being further provided with a projection to engage said partition, a spring interposed between the rearward part of the movable bar and the upper surface of the fixed bar, and a screw-bolt tapped through the main saddle and having its shank passed through the movable bar.

In testimony whereof I affix my signature in presence of two witnesses.

THOMAS H. LAVIER.
